UNITED STATES PATENT OFFICE.

EUGÈNIE M. DOWDELL, OF SAN FRANCISCO, CALIFORNIA.

AMUSEMENT DEVICE.

Application filed June 19, 1923. Serial No. 646,537.

To all whom it may concern:

Be it known that I, EUGÈNIE M. DOWDELL, a citizen of the United States, and resident of the city and county of San Francisco and 5 State of California, have invented certain new and useful Improvements in Amusement Devices, of which the following is a specification.

The present invention relates to amusement devices, and has for its principal object the provision of a means, adapted to be secured to the foot, whereby the healthful and pleasurable activities of children may be encouraged and promoted.

15 The device comprises a foot-supporting element fitted at its one extremity to receive the foot and bearing means for securing, or attaching, it thereto, and bearing at its other extremity a tread element adapted to permit a bouncing action.

Figure 1 is perspective view, showing the device in place.

Figure 2 is an elevation, partly in section, showing the foot-arch rest, the elastic-cushion tread, and a means for retaining the device in place.

Figure 3 is a plan view of Figure 2.

Figure 4 is a modification, showing a spherical tread, together with a flexible 30 buckle-bearing member for securing it in place.

In the preferred form of my invention, the spherical tread is comprised of a hollow 35 pneumatic element, but it is obvious that it might be a solid elastic element and still provide a useful device.

Referring more particularly to the drawings, 1 represents the foot-supporting element, 2 the foot-rest extremity, 3 the heel-check, 4 the vertically arranged cord channels, 4' the cords, 5 the rubber, or elastic, tread, 6 transverse aperture, 7 the flexible buckle-bearing member carried by the aperture 6, 8 the ball-tread, 9 the concavity in which rests the ball-tread 8, 10 the apertured plate for retaining the ball-tread 8 in place, and 11 the means for securing plate 10 to the base-extremity of element 1.

The preferred form of my invention, as shown in Fig. 4, comprises an elastic or gas 50 filled cushion element 8.

Having thus described my invention, what I claim and desire to secure by Letters Patent is:

1. A device of the class described, comprising a foot support having a cut out portion at one extremity constituting a heel rest and a cut out portion at the opposite extremity, and a pneumatic tread in the last named cut out portion. 55

2. A device of the class described, comprising a vertically elongated foot support, said support having means forming a rest for the sole of the shoe and a cut out portion forming a rest for the heel at one extremity thereof, said support having a rounded cavity at its opposite extremity, and a gas filled ball member seated in said rounded cavity. 60 65

EUGÈNIE M. DOWDELL.
